UNITED STATES PATENT OFFICE.

JACQUES COENRAAD HARTOGS, OF ARNHEM, NETHERLANDS.

TYING UP OF YARNS.

Application filed March 15, 1928, Serial No. 262,003, and in the Netherlands March 19, 1927.

In order to prevent the hanks of textile yarns becoming disarranged, they are provided at various places with a tie-up thread or hank tie. This is usually effected by hand, which however may easily cause damage to and irregularity of the threads, more particularly in the case of artificial silk. A tie-up needle is sometimes used. For dividing up the hanks into bundles a tie-up comb 5 is used, having teeth of equal length.

My present invention relates to a comb in which the gaps between the teeth are of different depth, alternately deep and short. On such a comb being inserted into a hank, 15 the yarn bundles become crossed, so that an opening or shed is produced, through which the tie-up thread can readily be introduced, the thread passing over one bundle and under the other.

20 If according to my invention a second similar comb be used at the same time, having however a short gap at the places between the teeth, where the first comb has a deep gap or vice versa, and if this second 25 comb be placed at some distance from the former one into the hank, an opening is also obtained for returning the tie-up thread, such that a bundle which on the thread being introduced was above the latter, is now below the same. The ends of the tie-up thread 30 come together again and can be knotted. By using two similar tie-up combs the tie-up thread can thus be passed conveniently and rapidly through the hank. The two 35 combs may be separate or may be combined in any suitable manner.

Figure 1 shows a constructional example of my invention, two parallel combs being illustrated in perspective view.

40 Fig. 2 shows a perspective view of an arrangement in which two similar combs are combined and held together.

The comb 1 is provided with teeth 2, the gaps 3, 4 between which are alternately deep

and short. In the comb 5 the gaps 3, 4 are 45 also alternately deep and short, but the deep gaps 3 are in the same position as the short gaps in the comb 1.

By inserting the combs 1 and 5 in the hank 6 the latter is divided up into bundles 50 7 and 8, so that openings are formed between the bundles, through which tie-up threads can be passed as indicated by the arrows 9 and 10.

As already stated, two or more combs 1, 55 5 can be fixed with respect to one another in such a way that a deep gap 3 of the comb 5 will lie opposite a short gap 4 in the comb 1. Such a construction is shown in Fig. 2 of the drawings.

I claim:

1. A tie-up comb which is inserted in hanks in order to enable tie-up threads to be passed through openings between the bundles, containing a number of teeth, the 65 gaps between the teeth having unequal depth, being alternately deep and short.

2. A device for tying up yarns, comprising a plurality of combs according to claim 1 fixed together, the different combs being 70 so positioned with respect to one another that a short gap in one comb will lie opposite a deep gap in the other comb.

3. A method of tying up yarns by using combs which are inserted in hanks in order 75 to enable tie-up threads to be passed through openings between the bundles, containing a number of teeth, and pass between the teeth having unequal depth, alternately deep and short, characterized by the feature that 80 the combs are inserted in the yarn in such a manner that a short gap between the teeth of one comb is positioned opposite a deep gap between the teeth of the other comb or vice versa.

85 In testimony whereof I affix my signature.

JACQUES COENRAAD HARTOGS.
